UNITED STATES PATENT OFFICE.

JOHN ANDERSON, OF BRADFORD, PENNSYLVANIA.

FOLDING BABY-CARRIAGE.

SPECIFICATION forming part of Letters Patent No. 628,295, dated July 4, 1899.

Application filed August 18, 1897. Serial No. 648,620. (No model.)

To all whom it may concern:

Be it known that I, JOHN ANDERSON, of Bradford, in the county of McKean and State of Pennsylvania, have invented certain new and useful Improvements in Folding Baby-Carriages; and I do hereby declare the following to be a full, clear, and exact description of the invention, such as will enable others skilled in the art to which it appertains to make and use the same.

This invention relates to improvements in folding baby-carriages; and it consists in the novel combination and arrangement of simple parts adapted to be folded together when not in use.

The object of my invention is to produce a simple and durable carriage of the kind specified that can be folded into compact form to be stored when not desired for use and one which can be readily fitted up as a sleigh or a cradle when desired.

Many advantages of my improved carriage will become apparent in the course of the following description, and the points of novelty will be particularly pointed out in the claims.

I am enabled to accomplish the objects of my invention by the means illustrated in the accompanying drawings, in which—

Figure 1 represents a perspective view of my improved carriage. Fig. 2 is a plan view of the axles of the carriage, the folded position thereof being shown in dotted lines. Fig. 3 represents an elevation of the folding body with rockers attached thereto to form a cradle. Fig. 4 is a perspective of sleigh-runners adapted to support and carry my folding baby-carriage body. Fig. 5 is a perspective of the body of the carriage with the sides and ends folded.

Referring to the drawings, the numeral 1 indicates the body of the carriage, and 2 the bottom thereof, hinged at or near its center, as indicated by the numeral 3.

The numeral 4 indicates the ends of the carriage-body, which are formed in two pieces 5 and 6, hinged, as indicated at 7, and adapted to be folded inwardly.

The numeral 8 indicates the sides of the carriage, which are also formed in two pieces 8 and 10 and hinged, as indicated at 11. The side pieces are provided with short pivoted arms 12 upon their upper end edges, which

are perforated for the reception of pins 13, which pass through said arms and into a perforation made in the upper side edges of the end pieces 6. The side pieces 5 and 6 are further provided with hooks 14 at their end edges, which are adapted to engage the eyes or projections 15, provided on the end of the carriage-body. The pivoted arms 12, the pins 13 passing therethrough, and the hooks and projections form a convenient means for securely holding the carriage-body in unfolded position. The sides 8 of the body are hinged to the bottom by hinges 16, which have one leaf attached to the side sections 9 and 10 on opposite sides of the body and are adapted to fold inwardly when the body is being folded.

The numeral 17 indicates the axles of the carriage, which are attached to the under side of the bottom of the body by means of springs 18, which are secured to the axles and the body of the carriage by screws or any other convenient means.

The axles 17 are each formed in two parts 19, hinged at or near their centers by a hinge 20, which permits them to be folded inwardly. Pivotedly attached to the inner sides of said axles and on either side of the centers thereof are four arms 21, which extend to a point at 80 or about midway between said axles, where they are turned inwardly and hinged together, as indicated at 22. The axles are provided with shoulders and reduced portions at their ends for the reception of wheels, as usual. 85

The numeral 23 indicates a pair of rockers which are provided with two upright arms 24 and a transverse arm 25, which are provided with perforations near their ends for the reception of grooves or bolts, which serve as 90 means for attaching the rockers to the carriage-body.

The numeral 26 indicates two sleigh-runners, which are connected at their upper sides by bars 27, which have their ends turned under, as indicated by the numeral 28, for the reception of a bolt, which serves to draw the parts together. 95

The numeral 29 indicates two braces which span the space between the runners and are attached thereto at their lower ends by means of screws 30 and at their upper portion to the bars 27 by means of bolts 31, which pass through the said braces and bar 27 and

through the bottom of the carriage-body, where they are provided with nuts to secure the runners to the body.

The handle 32 is provided at its lower end 5 with perforated metallic portions 33, which are adapted to fit around the under side of the axle and be secured thereto by screws or bolts.

When it is desired to fold the body, the pins 13 are removed and the hooks unhooked, 10 when one side is folded inward, turning on the hinge 16 until it is against the bottom of the body, when the piece 9 is folded, turning upon hinge 11 until it is in folded position upon the piece 10. The opposite side of the 15 body is folded on hinge 11 and then moved inward and folded upon the bottom of the body. For convenience the end pieces 6 are folded inwardly upon the already-folded portions, and the bottom pieces are folded until 20 the whole structure assumes the position shown in Fig. 6.

Many changes and modifications may be made without changing the character of my invention or departing from the spirit thereof.

25 Having thus fully described my invention, what I claim, and desire to secure by Letters Patent, is—

1. A baby-carriage body involving the combination of a bottom made in sections hinged

together to fold outward and back against 30 each other, sides made in sections, one of the side sections being hinged to the bottom section to swing inward against the bottom section, and the other side section being hinged to its complement to swing outward, ends 35 made in sections hinged together to fold over the free ends of the folded sides, substantially as described.

2. The combination of a suitable collapsible carrier or support, and a baby-carriage body 40 composed of a bottom made in sections hinged together to fold outward and back against each other, sides made in sections, one of the side sections being hinged to the bottom section to swing inward against the bottom 45 section and the other side section being hinged to its complement to swing outward, and ends made in sections hinged together to fold over the free ends of the folded sides, substantially as described.

50 In testimony whereof I have signed this specification in the presence of two subscribing witnesses.

JOHN ANDERSON.
